UNITED STATES PATENT OFFICE.

FREDERICK NAUDS, OF NEW YORK, N. Y.

DESIGN FOR A PATTERN-PLATE FOR GARMENTS.

SPECIFICATION forming part of Design No. 28,880, dated June 14, 1898.

Application filed May 12, 1898. Serial No. 680,519. Term of patent 7 years.

To all whom it may concern:

Be it known that I, FREDERICK NAUDS, of New York city, county and State of New York, have invented and produced a new and original Design for a Pattern-Plate for Garments, of which the following is a specification, reference being had to the accompanying drawings, in which—

Figure 1 is a face view of my newly-designed pattern-plate for garments; and Fig. 2, a section on line 2 2, Fig. 1.

The leading feature of my design consists of a pattern-plate for garments made in the form of a trapezium having two pairs of unequal sides inclosing differently-sized angles and provided on its face with lines extending transversely to such sides.

a b c d are the four sides of the trapezium-shaped pattern-plate *P*, and *A B C D* are its angles. The sides *a b* are equal to one another, and the sides *c d* are also equal to one another, but longer than the sides *a b*, so that the angle *C* is smaller than the angle *A*, while the angle *B* is equal to the angle *D*. 20

Along each of the sides *a b c d* extend lines *a' b' c' d'*, parallel to their respective sides and intersected by transverse lines *a² b² c² d²*. 25

What I claim is—

The design for a pattern-plate for garments, substantially as herein shown and described. 30

FREDERICK NAUDS.
